VOLTAGE CONTROL DEVICE

Yasunosuke Torii, Musashino-shi, Tokyo, Japan, assignor to Tokyo Shibaura Electric Co., Ltd., Kawasaki-shi, Japan, a corporation of Japan

Filed Dec. 7, 1964, Ser. No. 416,245

2 Claims. (Cl. 323—43.5)

This invention relates to a voltage control device and more particularly to a device for supplying variable alternating current voltage to a load and is especially useful to supply variable voltage to traction motors of an AC electric car through a car mounted transformer provided with a plurality of voltage regulating taps.

It is an object of this invention to provide an improved voltage control device which is simple in construction and light in weight.

A further object of this invention is to provide a voltage control device for AC electric cars which can provide a larger number of notches with less number of taps and contactors than conventional speed control devices.

For a more complete understanding of this invention reference may be had to the following detailed explanation in connection with the accompanying drawings in which:

FIG. 1 shows a connection diagram of a typical main circuit of a conventional control device for an alternating current electric car;

FIG. 2 shows a sequence table of tap-changing operation of the control device shown in FIG. 1;

FIG. 3 shows a connection diagram of the main circuit of a control device embodying this invention for an alternating current electric car;

FIG. 4 shows a sequence table of tap-changing operation of the control device shown in FIG. 3; and

FIGS. 5 and 6 show portions of the main circuits of another embodiment of this invention.

Referring first to FIG. 1 of the accompanying drawing illustrating a connection diagram of a conventional control device there is mounted on an electric car a transformer 1 having a primary winding P connected between a pantograph PG and the earth, and a secondary winding S provided with say 6 taps T₁ to T₆ inclusive over about one half of its length. Across the secondary winding S is connected a slidable resistor RH having high and low voltage terminals H and L. A sliding arm 2 of the slidable resistor RH is connected to one terminal of a load 3, or traction motors in this embodiment. As shown in FIG. 1, taps T₁ to T₆ are provided on the lower half of the secondary winding adjacent its low voltage terminal, add numbered taps T₁, T₃ and T₅ being connected to one bus bar 4 via contactors C₁, C₃ and C₅, respectively, while the even numbered taps T₂, T₄ and T₆ to the other bus bar 5 via contactors C₂, C₄ and C₆, respectively. A current balancing reactor 6 is connected across bus bars 4 and 5 with its mid point 7 connected to the opposite side of the load 3.

As shown in the notch sequence table, shown in FIG. 2, at the first notch the sliding arm 2 of the resistor RH is positioned on the L side and the contactors C₁ and C₂ are closed. Thus the bus bars 4 and 5 are connected to the taps T₁ and T₂ so that a voltage intermediate these taps will be supplied to the load 3. At the second tap the contactor C₁ is opened while contactors C₂ and C₃ are closed so that a voltage intermediate taps T₂ and T₃ will be supplied to the load. In this manner the voltage applied to the load will be gradually increased until the fifth notch is reached at which time a voltage intermediate the taps T₅ and T₆ will be supplied to the load 3. It is to be understood that, under this condition, a voltage corresponding to about one half of the voltage induced in the secondary winding S will be supplied to

2

the load. At the sixth notch the sliding arm 2 is transferred from L to H side but this will result in no change in the load voltage. At successive stages from seventh to tenth notches inclusive the respective contactors will be operated in an order reverse to that described above to successively add intermediate tap voltages to one half of the secondary voltage so that at the final or tenth notch full secondary voltage will be supplied to the load 3.

While with the above described prior arrangement the number of taps and hence the number of contactors can be considerably reduced since these taps are required to be provided for only one half of the secondary winding to gradually increase the load voltage from minimum to the full secondary voltage, there are such defects that it requires to provide a resistor RH which normally consumes substantial amount of electric power and also requires to use a mechanism to transfer between L and H side terminals of the resistor RH. Moreover, when it is desired to increase the number of notches, the number of taps and contactors must also be increased, thus resulting in a complicated construction of the transformer winding.

Thus, it is the feature of this invention to provide a novel voltage control system, which is especially suitable for use in electric cars and can provide a larger number of notches with relatively small number of taps and contactors.

An illustrative example of this invention as applied to speed control of an alternating current electric train will now be described by referring to FIG. 3, wherein the same or corresponding parts are designated by the same reference characters as in FIG. 1. In this embodiment the transformer 1 is provided with three secondary windings S₀, S₁ and S₂. Among these, the winding S₀ alone is provided with five voltage regulating taps T₁ to T₅ inclusive for example and thus termed as the voltage regulating winding. It is designed that the secondary winding S₁ will induce a voltage which is equal to the sum of the voltage of the winding S₀ and the tap voltage and that the secondary winding S₂ a higher voltage which is equal to the sum of the voltages of windings S₁ and S₀ and the tap voltage of the winding S₀. The odd numbered taps T₁, T₃ and T₅ of the voltage regulating winding S₀ are connected to a bus bar 4 respectively through contactors C₁, C₃ and C₅ while the even numbered taps T₂ and T₄ to a bus bar 5 through contactors C₂ and C₄ respectively. A balancing reactor 6 is connected across bus bars 4 and 5 with its mid point connected to one terminal of the load 3. The upper terminal of the winding S₁ is connected to the bus bar 5 through a contactor C₆ while the upper terminal of the winding S₂ is also connected to the same bus bar through a contactor C₇. The lower terminals of the windings S₁ and S₀ are connected to the other or grounded terminal of the load 3 through contactors C₈ and C₉, respectively, while the lower terminal of the winding S₂ is directly connected to said grounded terminal. The junction between the lower terminal of the voltage regulating winding S₀ and the contactor C₈ is connected to the upper terminal of the winding S₁ through a contactor C₁₀ and also to the upper terminal of the winding S₂ through a contactor C₁₁. The lower terminal of the winding S₁ is connected to the upper terminal of the winding S₂ through a contactor C₁₂.

With reference to the notch sequence table of the above described control device, shown in FIG. 4, it will be noted that at the first notch, contactors C₁ and C₈ are closed to apply the voltage appearing at the first tap T₁ of the regulating winding S₀ to the load 3 through the bus bar 4. At the second notch the contactor C₂ will also be closed to apply a voltage intermediate the taps T₁ and T₂ to the load through bus bars 4, 5 and the reactor 6. At the third notch the contactor C₁ will be opened and

instead the contactor C_3 closed to apply a voltage applied to the load will be increased gradually. Upon reaching the sixth notch, the regulating windings S_0 and S_1 will be connected in parallel with respect to the load through the reactor 6 by the closure of contactors C_5 , C_8 , C_9 and C_6 whereby to apply to the load a voltage intermediate the voltage of the winding S_1 and the voltage of the highest tap T_6 of the winding S_0 .

At the seventh notch contactors C_5 and C_8 will be opened and instead contactors C_1 and C_{10} closed. As a result the upper terminal of the winding S_1 will be connected to the bus bar 4 in series with the tap T_1 of the resulting winding S_0 thus applying to the load a voltage which is equal to the sum of the voltage of the winding S_1 and the voltage of the tap T_1 of the winding S_0 . Thereafter the contactor C_6 will be opened and the same sequence of voltage control as has been previously described in connection with the notches 1 to 5 is repeated to further gradually increase the load voltage. At the twelfth notch contactors C_5 , C_9 , C_{10} and C_7 will be closed to connect a series combination comprising the windings S_0 and S_1 in parallel with the winding S_2 through the reactor 6 so that the voltage supplied to the load will be increased by the tap voltage of the regulator winding S_0 and the sum of the voltages of the windings S_0 and S_1 . Upon reaching the thirteenth notch the contactor C_9 will be opened while contactors C_1 , C_7 and C_{11} closed to connect the upper terminal of the winding S_2 to the bus bar 5 and also to connect the series combination comprising the winding S_2 and the tap T_1 of the winding S_0 to the bus bar 4 to further increase the load voltage. Thereafter the contactors C_1 to C_5 inclusive will be sequentially closed to gradually increase the load voltage by successively adding a voltage intermediate two adjacent taps to the voltage of the winding S_2 until the eighteenth notch is reached at which time the contactors C_5 and C_{11} will be closed. In order to further increase the load voltage to provide the highest voltage contactors C_{12} and C_{10} are closed to connect in series all of the voltage regulating windings S_2 , S_1 and S_0 .

FIG. 5 shows a connection diagram of a modified embodiment of this invention wherein in addition to the regulating winding S_0 with taps, three voltage regulating windings S_1 , S_2 and S_3 without tap are provided to increase the number of voltage regulating notches. In still further modification shown in FIG. 6 the number of voltage regulating notches is still further increased by providing four voltage regulating windings S_1 , S_2 , S_3 and S_4 without tap.

In the above arrangements embodying the principle of this invention if it is assumed that the number of voltage regulating windings without tap is equal to M and that the number of taps of the voltage regulating winding is equal to N , the number of contactors will be expressed by the following equation:

$$2M + \frac{M(M+1)}{2} + N$$

the number of lead wires

$$2M + (N+1)$$

and the number of notches

$$2^M \times N + 2^M - 1$$

By the arrangement shown in FIG. 3, the number of the notches can be made to be equal to 23 with five sections of the regulating windings S_0 , ten lead wires and twelve contactors, and by the arrangement shown in FIG. 4, the number of notches can be increased to 63 with seven sections of the regulating windings S_0 , 15 lead wires and 19 contactors whereas the number of the notches may be greatly increased to 169 with 9 sections of the regulating winding S_0 , 18 lead wires and 27 contactors.

Thus it will be seen that this invention provides considerably a large number of notches with relatively a small number of transformer taps and contactors whereby to simplify the construction of the transformer and reduce the number of parts requiring frequent repair and replacement.

While the embodiments of the invention as herein disclosed constitute preferred forms it is evident that other forms might be adapted. Thus, the control devices may be advantageously used in many applications where an alternating current voltage supplied to a load should be varied over a wide range.

What is claimed is:

1. A voltage control device comprising a source of alternating current, a load, a transformer connected between said source and said load, said transformer having a primary winding connected across said source of alternating current and a plurality of secondary windings, the first secondary winding being a regulating winding producing a voltage E and provided with a plurality of taps, the voltage between taps being E' , the second secondary winding providing a voltage $E+E'$, the third secondary winding producing a voltage $2(E+E')$, and n th secondary winding producing a voltage $2^{n-2}(E+E')$, a first group of contactors each associated with the respective one of said taps of said regulating windings, a second group of contactors connected between the high voltage side of each of the secondary windings and the low voltage side of the other of said secondary windings, means to operate said first and second groups of contactors such that the voltage supplied to said load is gradually increased in the first step, by said regulating winding, in the second step by serially connecting said regulating winding and said second secondary winding, in the third step by connecting in series said regulating winding with said third secondary winding, in the fourth step by connecting in series said first, second and third secondary windings, and in the n th step by connecting in series all of said secondary windings.

2. The voltage control device according to claim 1 wherein a reactor is provided with its mid-point connected to one terminal of said load and its opposite terminals connected to one of a pair of bus bars and alternate taps of said regulating winding are connected to different one of said bus bars through associated contactors.
